TABLE OR SIMILAR ARTICLE

William James Bargen, Waukegan, Ill.

Application April 10, 1953, Serial No. 24,430

Term of patent 14 years

(Cl. D33—14)

To all whom it may concern:

Be it known that I, William James Bargen, a citizen of the United States of America, residing at Waukegan, in the county of Lake and State of Illinois, have invented a new, original, and ornamental Design for a Table or Similar Article, of which the following is a specification, reference being had to the accompanying drawing forming a part thereof.

In the drawing:

The single figure is a perspective view of a table or similar article, showing my new design.

The dominant features of my design are shown in full lines in the drawing.

I claim:

The ornamental design for a table or similar article, as shown and described.

WILLIAM JAMES BARGEN.
